UNITED STATES PATENT OFFICE

WILLIAM C. EPSTEIN, OF DAYTON, OHIO, ASSIGNOR TO THE DUO-TOR MANUFACTURING COMPANY, OF DAYTON, OHIO, A CORPORATION OF OHIO

COMBINED INCINERATOR AND WATER HEATER

Application filed August 13, 1928. Serial No. 299,165.

This invention relates to a combined incinerator and water heater and is a continuation of the application filed by me June 15, 1927, Serial No. 198,892, in so far as the disclosure 5 is common to the two applications.

One object of the present invention is to provide such a combined incinerator or water heater which will have a high degree of efficiency as a water heater.

10 A further object of the invention is to provide a combined incinerator and water heater of such a character that a substantial portion of the water heating surfaces will be so arranged that the products of combustion of 15 the material being consumed will not come in contact therewith and consequently such surfaces will not become coated with grease or other matter given off by the material which is being consumed.

20 A further object of the invention is to provide such an apparatus with a receptacle for the material to be consumed of such a character that the lower portion thereof, which is subjected to the greatest heat, may be renewed when worn out without discarding the 25 receptacle as a whole.

A further object of the invention is to provide a combined incinerator and water heater having a main burner provided with inner 30 and outer gas outlets to direct the flame against the bottom of the receptacle for the material to be consumed and against the tank and having associated therewith a pilot burner of such a character that it will simultaneously ignite the gas at both the inner and 35 outer outlets of the main burner.

Other objects of the invention will appear as the apparatus is described in detail.

In the accompanying drawings Fig. 1 is a 40 vertical sectional view taken centrally through a combined incinerator and water heater embodying my invention; Fig. 2 is a transverse sectional view taken on the line 2-2 of Fig. 1; Fig. 3 is a plan view of a portion of the main burner showing the pilot burner partly broken away; Fig. 4 is a transverse section of the burner taken on the line 4-4 of Fig. 3; Fig. 5 is a vertical sectional view taken centrally through a modified form 45 of combined incinerator and water heater;

and Fig. 6 is a transverse section taken on the line 6-6 of Fig. 5 and partly broken away.

In these drawings I have illustrated one embodiment of my invention together with a slightly modified form thereof but it will be 55 understood that these embodiments have been chosen for the purposes of illustration only and that the apparatus may take various forms without departing from the spirit of the invention.

In that form illustrated in Figs. 1 and 2 the apparatus comprises a tank 1 which is annular in form and has an inner circumferential wall 2 and an outer circumferential wall 3, the inner and outer walls being connected at 60 their upper and lower ends respectively by a top wall 4 and a bottom wall 5. The outer circumferential wall 3 projects some distance below the bottom wall 5 and is provided with an inwardly extending annular flange or sub-bottom 6 having a central opening to receive a burner 7. The tank is preferably supported on legs 8 or similar supports so that the burner is some distance above the floor. Depending from the sub-bottom 6, about the 65 opening therein, is a housing 9 having inwardly extending brackets 10 on which the burner 7 is supported. This housing also has a flange 11 which cooperates with a latch 12 to removably support an ash pan 13.

70 Means are provided for supporting the material to be consumed within the central opening to the tank. This means may take various forms and may be wholly separate from the tank or it may utilize a portion of the tank in the supporting function. As here shown, a supporting structure is mounted on the upper end of the tank and consists of a ring or annular casting 14 secured to the tank about the upper end of the opening and comprising an inwardly extending portion 15 spaced from the top wall 4 of the tank and provided with an upwardly extending flange 16. Supported upon the inwardly extending portion 15 of the casting 14 and about the flange 16 is a housing 17, preferably cylindrical in form and having at its upper end an inwardly extending flange 18. Arranged within the opening in the tank is a hopper 19 which is preferably supported 75 80 85 90 95 100

wholly at its upper end upon the supporting structure consisting of the casting 14 and the housing 17. To this end a ring 20 is rigidly secured to the upper end of the hopper and has an outwardly extending portion which overlaps and is supported by the flange 18 of the housing, the two parts having contacting surfaces arranged to form a tight joint. Thus the hopper is supported wholly upon the housing and can be removed from the tank by merely lifting the same therefrom. A cover 21 is hinged to the ring 20 of the hopper to close the upper end thereof and prevent the escape of fumes. The hopper is, in the present instance, of a diameter somewhat less than the diameter of the opening through the tank, thereby providing between the hopper and the tank a passageway 22. The lower portion of the hopper is perforated and, in the present instance, the circumferential wall thereof is provided with slots 23 and the bottom wall 24 is slotted. As here shown, this bottom wall is in the form of a grate, the inner portion 25 of which is movable to facilitate the removal of ashes from the hopper. In the present construction, the bottom wall is flanged to embrace the lower end of the cylindrical wall of the hopper and is detachably secured thereto by bolts or screws 26, thus enabling the bottom wall to be removed and renewed if necessary.

I also prefer to so construct the hopper that the lower portion thereof, which is subjected to the greatest heat, may be removed and renewed independently of the upper portion. To this end the hopper is formed in two parts, the upper portion being removably supported on the tank and the lower portion, shown at 27, having lugs 28 overlapping the lower end of the upper portion and secured thereto by bolts 29. Preferably the upper end of the hopper is flared, as shown at 30, to facilitate the introduction of the garbage or other material into the same and the upper end of the inner wall of the tank is flared, as shown at 31, to maintain the proper spacing between the same and the flared portion of the hopper. The space or passageway 22 opens into the interior of the supporting structure, which constitutes an outlet passageway or chamber for the products of combustion and is provided with an outlet 32 adapted to be connected with a flue. The upper end of the hopper, which extends into this outlet chamber, is slotted, as shown at 33, to permit the fumes and gases to pass from the hopper to the outlet 32. As here shown, the flared upper end of the hopper is flat on that side adjacent to the outlet 32, as shown at 34, to avoid restricting the capacity of the outlet.

The products of combustion both from the burner 7 and from the material which is being consumed will act upon the inner

wall 2 of the tank to heat the water therein and the flame from the burner will also contact with the bottom wall 5 of that tank but in order to secure a more efficient heating of the water I have provided the tank with other passageways which extend through the same from end to end and are arranged to receive the products of combustion from the burner, thus carrying the same directly through the body of water in the tank. As here shown, these other passageways consist of conduits or tubes 35 mounted in the upper and lower walls of the tank a short distance from the inner wall 2 and spaced apart about that inner wall. Thus the lower ends of the tubes or passageways are so arranged that they will receive the products of combustion from the burner 7 but, being in the bottom wall of the tank, they will not receive any of the greasy gases or other products of combustion from the material which is being consumed within the hopper and consequently they will not become coated with such greases or other materials, which coating would tend to restrict the passage of heat through the same to the water. These passageways 35 open into the annular portion of the outlet chamber, formed between the portion 15 of the casing 14 and the top wall of the tank, so that all products of combustion are delivered to the outlet chamber. The portion 15 overlaps the upper ends of the passageways 35 and being spaced but a short distance therefrom tends to retard the flow of the products of combustion through these passageways and thus maintain the same for a longer time in contact with the walls of the passageways, causing more of the heat thereof to be taken up by the water.

The burner 7 which is shown in detail in Figs. 3 and 4 is preferably annular in form and is provided with inner and outer gas outlets so arranged that the flame from the inner outlet will be directed against the bottom of the hopper and the flame of the outer outlet will be directed against the bottom of the tank and through the passageways 22 and 35. As here shown, the burner comprises a lower portion 36 and an upper portion 37 spaced from the lower portion to provide slots 38 and 39 at the inner and outer edges, respectively, of the burner. The upper portion also has inwardly and outwardly projecting portions 40 and 41 overhanging the slots to prevent the entrance of foreign matter to the burner. The burner 7 is preferably automatically controlled by means of a thermostat in the tank or elsewhere. This method of control being well known and forming no part of the present invention is not here shown. Because of the character of the burner, it is necessary that the pilot burner shall be of such a character as to instantly ignite the gas at both

the inner and outer outlets of the burner and for this purpose I have provided a special pilot burner. Preferably this pilot burner is arranged above the annular burner and has gas outlets directed respectively toward the inner and outer sides of the annular burner, it being understood that the gas from these outlets burns continuously. In the present construction the pilot burner is in the form of a housing 42 mounted on the top wall 37 of the burner 7 and connected thereto by a supply pipe 43 which extends through the two parts of the burner 7. At the upper end of the supply pipe 15 the housing 42 is provided with oppositely directed gas outlets or jets 44 directed respectively toward the inner and outer sides of the annular burner, the housing 42 having lateral openings 45 to permit the passage of the gas. Thus it will be apparent that when the pilot burner is ignited it will project a jet of flame above both the inner and outer gas outlets of the annular burner and when the gas valve is opened the gas 20 will be ignited instantly on both sides of the burner.

That form of the apparatus shown in Figs. 5 and 6 is substantially similar to the form above described with the exception that it 25 employs a slightly different means for supporting the material to be consumed and has the passageways through the tank arranged in a slightly different manner. As here shown, it comprises a tank 46 having an outer wall 47 and an inner wall consisting of an upper portion 48 and a lower portion 49, the lower portion being of a diameter substantially greater than the upper portion. Thus the inner wall provides an opening 30 through the tank which is of less diameter at its upper end than it is at its lower end. The smaller upper portion 48 of the inner wall is utilized in part to support the material to be consumed and, as here shown, it 35 extends slightly below the upper end of the larger part 49 of the inner wall, as shown at 50, and has detachably secured thereto a receptacle or basket 51 which is apertured in its bottom and circumferential walls and 40 is arranged directly above the burner 52, which is arranged below the opening through the tank. A supporting structure or top casting 53 is supported on the upper end of the tank and a short hopper 54 is supported on this casting and extends into the 45 upper portion of the opening through the tank to guide the material into the receptacle. This supporting structure is hollow and of a greater diameter than the hopper 54 and 50 constitutes an outlet chamber for the products of combustion, the hopper 54 being slotted, as shown at 55, to permit the products of combustion to pass through the outlet chamber to an outlet 56. Passageways are 55 provided to carry the products of combustion

through the upper portion of the tank and, as here shown, these passageways are in the form of conduits 57 secured to the upper portion 48 of the inner wall of the tank and extending for the full length of that portion of the inner wall, thus connecting the enlarged lower portion of the opening with the outlet chamber in the supporting structure 53 and carrying the products of combustion through the water in the tank, it being noted that three walls of each passageway 57 are in contact with the water.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In a combined incinerator and water heater, a tank for water to be heated having a passageway extending therethrough and constituting a combustion chamber, a burner arranged beneath said combustion chamber, and means for supporting material to be consumed within said combustion chamber, said tank having a passageway other than said combustion chamber extending through the water therein and arranged to receive products of combustion from said burner.

2. In a combined incinerator and water heater, a tank for water to be heated having a passageway extending therethrough and constituting a combustion chamber, a burner arranged beneath said combustion chamber, and means for supporting material to be consumed within said combustion chamber, said tank having a passageway other than said combustion chamber extending through the water therein and having its lower end so arranged that it will receive products of combustion from said burner but will not receive products of combustion from the material in said combustion chamber.

3. In a combined incinerator and water heater, a tank having inner and outer circumferential walls, the inner wall forming a vertical opening through the tank which constitutes a combustion chamber, a burner supported beneath said combustion chamber, and means for supporting material to be consumed within said combustion chamber, said tank having a plurality of passageways extending through the same between said inner and outer walls, spaced apart about said combustion chamber and arranged to receive products of combustion from said burner.

4. In a combined incinerator and water heater, a tank for water to be heated having a passageway extending therethrough and constituting a combustion chamber, a burner arranged beneath said combustion chamber, means for supporting material to be consumed within said combustion chamber, said

10 tank having a passageway other than said combustion chamber extending through the water therein and arranged to receive products of combustion from said burner, and a structure supported on the upper end of said tank and having a chamber communicating with said combustion chamber and said passageway and having an outlet for the products of combustion.

15 5. In a combined incinerator and water heater, a tank for water to be heated having a passageway extending therethrough and constituting a combustion chamber, a burner arranged beneath said combustion chamber, and means for supporting material to be consumed within said combustion chamber, said combustion chamber being arranged to provide a passageway for products of combustion about said material and said tank having a passageway for products of combustion extending through the water therein from a point adjacent to said burner and separate from said combustion chamber.

20 6. In a combined incinerator and water heater, a tank having an opening therethrough constituting a combustion chamber, a receptacle for material to be consumed supported within said combustion chamber and spaced from the wall thereof, a burner arranged beneath said combustion chamber, and conduits extending through said tank and arranged to receive the products of combustion from said burner.

25 7. In a combined incinerator and water heater, a tank having inner and outer circumferential walls and end walls, said inner wall forming a vertical opening through said tank, said opening constituting a combustion chamber, a receptacle for material to be consumed supported in said combustion chamber, a burner mounted beneath said combustion chamber, and conduits mounted in said end walls, extending through said tank and spaced from said inner and outer walls.

30 45 8. In a combined incinerator and water heater comprising a tank having an opening through the same constituting a combustion chamber, and a burner mounted beneath said combustion chamber, a hopper arranged within the combustion chamber and comprising an upper portion removably supported on said tank and a lower portion extending to a point adjacent to said burner, and means for detachably securing said lower portion to said upper portion.

35 60 9. In a combined incinerator and water heater, a tank having an opening therethrough constituting a combustion chamber, a burner arranged beneath said combustion chamber, means for supporting material to be consumed within said combustion chamber, said supporting means comprising an upper part carried by said tank and a separate lower perforated part and means for detachably

390 connecting said lower part, with and supporting the same from said upper part.

395 In testimony whereof, I affix my signature hereto.

400 WILLIAM C. EPSTEIN.
